[57] CLAIM

The ornamental design for a facsimile transceiver, as
shown and described.

DESCRIPTION

FIG. 1 is a top, front and right side perspective view of
a facsimile transceiver showing our new design;
FIG. 2 is a front elevational view thereof;
FIG. 3 is a top plan view thereof;
FIG. 4 is a right side elevational view thereof, the left
side being a mirror image;
FIG. 5 is a rear elevational view thereof; and,
FIG. 6 is a bottom plan view thereof.

*FIG. 1**FIG. 2**FIG. 3**FIG. 4**FIG. 5**FIG. 6*
